UNITED STATES PATENT OFFICE.

WILFRED I. OHMER, OF DAYTON, OHIO, ASSIGNOR TO THE RECORDING AND COMPUTING MACHINES COMPANY, OF DAYTON, OHIO, A CORPORATION OF OHIO.

FARE-BOX.

1,246,645.

Specification of Letters Patent. Patented Nov. 13, 1917.

Original application filed December 30, 1911, Serial No. 668,612. Divided and this application filed April 3, 1916. Serial No. 88,670.

To all whom it may concern:

Be it known that I, WILFRED I. OHMER, a citizen of the United States, residing at Dayton, in the county of Montgomery and State of Ohio, have invented certain new and useful Improvements in Fare-Boxes, of which the following is a specification, reference being had therein to the accompanying drawing.

10 This invention relates to fare boxes and was fully described and shown in applicant's co-pending application, filed Dec. 30, 1911, Ser. No. 668,612, the present application constituting a division thereof.

15 The object of the invention is to provide in a fare box a compartment for transfers, tickets and the like having devices to mark the same as they are deposited with the time of their receipt and, if desired, the line number and another number.

20 In the accompanying drawings, Figure 1 is a section taken on the line 2-2 of Fig. 2, looking in the direction of the arrows and showing the marking mechanism of the 25 transfer portion of the fare box; Fig. 2 is a section on the line 1-1 of Fig. 1, looking in the direction of the arrows; Fig. 3 is a section taken centrally through the time, date and line numbering devices; Fig. 4 is 30 a section taken on the line 3-3 of Fig. 3 and looking in the direction of the arrows; Fig. 5 is a front elevation of the time, date and line number printing devices; and Fig. 6 is a sectional view taken centrally through 35 the consecutive number printing devices.

40 In these drawings I have illustrated one embodiment of my invention and have shown the fare box for transfers as comprising a suitable receptacle 85 into which the transfers and the like are fed. The transfers after being marked fall into a suitable receptacle at the bottom of the receptacle 85, such as a drawer which is not shown. The receptacle is provided with a suitable chute 45 86 through which the transfer may be inserted into the box. Mounted in the transfer portion of the box, which will be termed the transfer box, is suitable mechanism for canceling or printing upon the transfer certain 50 desirable data. In the present instance this data includes the date, the time the transfer is received, the line number and also another number. Further, the present device is provided with a visual counter which displays

the number printed upon the transfer. It 55 will be understood that the mechanism for printing this data may be of any suitable character. For the purpose of illustrating the invention I have here shown the same as comprising a printing cylinder 87 upon 60 which the printing devices are mounted and a platen 88 arranged to coöperate with the printing devices of the cylinder 87. The printing cylinder and the platen are journaled in the frame of the transfer box and 65 are so arranged with reference to the chute 86 that a transfer inserted through the chute will engage the adjacent portions of these 70 printing devices, and the rotation of one of the devices will cause the transfer to be gripped between them and simultaneously 75 drawn into the box and marked with the desired data, which marking not only makes a record of this data but also serves to cancel the transfer. Mounted in the printing cylinder 87 are three groups of printing counters, indicated by the reference numerals 89, 90 and 91. The first group, 89, is adapted 80 to print the hour and minute at which the transfer is received. The third group, 91, will print the day of the month on which the transfer is received and the second group, 90, will print the number of the particular line on which the car is running. These 85 printing devices are of well known construction and are set by hand to print the desired data. Each printing wheel is loosely mounted upon a shaft 92 mounted in the cylinder 87 eccentrically to the axis thereof and each counter wheel is provided with 90 the usual gear, indicated at 93, which meshes with a corresponding gear 94. These latter gears are mounted on an axis coincident with the axis of rotation of the cylinder 87 and each gear 94 is carried by a sleeve 95, 95 the several sleeves which extend beyond the same end of the cylinder being nested in a well known manner. At its outer end each sleeve is provided with a knurled knob or hand wheel 96 by means of which the corresponding gear 94 may be rotated and the counter wheels adjusted to the desired point. The cylinder is, in the present instance, rotated by means of gearing, one of the gears, 97, being rigidly secured to the end of the 100 cylinder and meshing with a second gear 98 mounted on a shaft 99 extending beyond one side of the fare box and provided with a

handle 100. If desired, a suitable stop may be provided, as shown at 101, to stop the rotation of the handle when it has completed a single revolution and thus cause the counters to be aligned in printing position. It will be noted that the opposite end portions of the cylinder 87 are of relatively great width. These are adapted to engage the edges of the transfer and press the same against the platen roller and these parts of the cylinder, together with the platen, constitute feeding devices for feeding the transfer into the transfer box.

The consecutive number printing device, which is also carried by the printing cylinder 87, may be of any suitable character and is here shown as of a well known type. As shown, it comprises a series of printing counters 102 each having an operating gear 103 and each being loosely mounted upon a shaft 104. This shaft is rotatably mounted in the end walls of the cylinder. It will be noted that one end of the shaft 104 extends loosely through the adjacent end of the cylinder 87 and is journaled in a hood or extension 105 mounted on the outer surface of this wall of the cylinder. It will be further noted that a sleeve 106 is mounted upon the shaft 104 and extends through the opening in that end of the cylinder carrying the hood or extension 105. The inner end of this sleeve is rigidly secured to the units counter wheel 102 and the outer end has rigidly secured thereto in the space between the hood 105 and the adjacent end of the cylinder a gear 107 adapted to engage a fixed stop which, in the present instance, comprises a one-toothed gear 108 mounted on the end of the casing in a position to engage the teeth of the gear 107, (see Fig. 2). Each revolution of the printing cylinder will, therefore, cause the gear 107 to engage the tooth 108 and will advance the units counter one step. This movement is transferred from the units counter to the succeeding counters by transfer mechanism of any suitable character and as that here shown is of ordinary construction and forms no part of the present invention it is not necessary that it should be described. The printing counters 102 may be so mounted that they can be reset to zero at the end of a given period and a new count started or they may be such that they cannot be reset and will continue to count on indefinitely, thus registering every transfer received from the time the device is installed up to 99,999. In the present instance I have illustrated the shaft 104 as a resetting shaft of a well known character which need not be described here, it being sufficient to note that the rotation of the shaft by means of a suitable key or wrench applied to the squared head 109 will cause all of the counter wheels to be returned to zero.

The device for inking the printing counters may also be of any suitable character. In the present instance it consists merely of an inking roll 110 journaled in the frame or casing 85 at a point where it will come in contact with the printing counters before the latter engage the transfer to print thereon.

It is also desirable that a visual indicator should be provided to indicate the number which has been printed upon the transfer. For this purpose the top wall of the casing 85 may be provided with a sight opening 111 and a series of counters 112 mounted within the casing in a position to be read through this opening. This visual counter may be of any of the usual types and as here shown the initial movement is imparted thereto by the usual star wheel 113 adapted to be engaged by a tooth or projection 114 mounted on the edge of the printing cylinder 87 so that each rotation of the cylinder will not only advance the printing counters 102 one point but will likewise advance the visual counters one point, thereby causing the visual counters to indicate the number which will be printed upon the next transfer which is fed into the box.

It is thought the operation of the mechanism will be readily understood from the foregoing description and it will be apparent that I have provided a transfer box adapted to print certain data upon each transfer deposited within the same.

While I have shown and described one embodiment of the invention it will be understood that the invention does not reside in the specific devices which I have employed in carrying out the present embodiment and any suitable devices may be substituted for those here shown and the arrangement of the device correspondingly altered. It will, therefore, be further understood that I do not wish to be limited to the details of construction shown and described, for obvious modifications will occur to a person skilled in the art. It will also be understood that devices for printing the data on the transfer are not limited to this use but are of general application and may be utilized to print the date and number, or other data on certificates or coupons of various kinds.

Having thus fully described my invention, what I claim as new and desire to secure by Letters Patent, is:

1. In a fare box having a transfer compartment, a feed chute converging downwardly from the outside of the box and provided with an opening at its lower end, a rotatable drum journaled in said compartment adjacent the opening and a platen constituting feeding devices likewise mounted adjacent the opening, printing devices rotatably mounted on said drum, axially ar-

- ranged devices for adjusting said printing devices, devices to print a consecutive number rotatably mounted on an axis spaced around the drum from the axis of said first- 45
 5 mentioned printing devices, means on the frame of the compartment for advancing said last mentioned printing devices at each revolution of the drum, and means for rotating the drum.
- 10 2. In a fare box having a transfer compartment, a feed chute converging downwardly from the outside of the box and provided with an opening at its lower end, a rotatable drum journaled in said compartment with its periphery adjacent said opening, a platen likewise mounted adjacent the opening and coöperating with said drum, printing devices rotatably mounted on said drum, axially arranged devices for adjusting said printing devices, devices to print a consecutive number rotatably mounted on an axis spaced around the drum from the axis of said first mentioned printing devices, and provided with a gear fixed thereto, a fixed 60
 15 projection directly and periodically engaging the teeth of said gear to advance the consecutive numbering devices at every revolution of the drum, and means for rotating the drum.
- 20 3. In a fare box having a transfer compartment, a feed chute converging downwardly from the outside of the box and provided with an opening at its lower end, a rotatable drum journaled in said compartment with its periphery adjacent said opening, a platen adjacent said opening and coöperating with said drum, printing devices rotatably mounted on said drum, axially arranged devices for adjusting said printing devices, devices to print a consecutive number rotatably mounted on an axis spaced around the drum from the axis of said first mentioned printing devices, and provided with a gear fixed thereto, a fixed 65
 25 projection directly and periodically engaging the teeth of said gear to advance the consecutive numbering devices at every revolution of the drum, and means for rotating the drum.
- 30 4. In a fare box having a transfer compartment, a feed chute converging downwardly from the outside of the box and provided with an opening at its lower end, a rotatable drum journaled in said compartment with its periphery adjacent said opening, a platen adjacent said opening and coöperating with said drum, printing devices rotatably mounted on said drum, axially arranged devices for adjusting said printing devices, devices to print a consecutive number rotatably mounted on an axis spaced around the drum from the axis of said first mentioned printing devices, and provided with a gear fixed thereto, a fixed projection directly and periodically engaging the teeth of said gear to advance the consecutive numbering devices at every revolution of the drum, an indicator actuated by said drum, and means for rotating the drum. 70
 35
 40
5. In a device of the character described, a frame, a rotatable drum mounted on said frame, a platen coöperating with said drum and constituting therewith feeding devices, printing devices rotatably mounted on said drum, axially arranged devices for adjusting said printing devices, devices to print a consecutive number rotatably mounted on an axis spaced around the drum from the axis of said first mentioned printing devices, and provided with a toothed gear fixed to said last mentioned printing devices, a fixed projection adapted to directly and periodically engage said gear to advance said consecutive numbering devices at every revolution of the drum and means for rotating the drum. 75
 80

In testimony whereof, I affix my signature. 85
 WILFRED I. OHMER.
